APPARATUS FOR BULKING YARN

Dimitri G. Soussloff and Edward J. Duggan, Warwick, and Theodore A. Whiting, Warren, R. I., assignors to Universal Winding Company, Cranston, R. I., a corporation of Massachusetts

Application January 13, 1954, Serial No. 403,818

3 Claims. (Cl. 28—1)

The present invention relates to a machine for imparting bulk to a strand of twisted continuous filament yarn, and more particularly pertains to such a machine adapted to form loops in the individual filaments which make up the strand.

It has been discovered that if a twisted strand of continuous filament yarn is passed through an aspirator, and is drawn away from said aspirator at substantially 90° as soon as it emerges therefrom, many of the filaments making up the strand are thrown out from the strand in the form of loops which give bulk thereto and which simulate the appearance of spun yarn. Heretofore, this process of imparting bulk to continuous filament yarn has been difficult to accomplish due to difficulty in feeding the yarn to the aspirator at a constant predetermined speed, withdrawing the yarn from the aspirator at a speed that is a predetermined fraction of the speed with which it is fed thereto to allow for the shortening of the strand that takes place as its diameter is increased, and the necessity for stretching the bulked yarn a small amount to standardize its diameter and to remove any irregularities therein. Furthermore, prior to the present invention great difficulty has been experienced in starting the bulking operation inasmuch as the feeding, withdrawing and stretching steps must be started simultaneously and in synchronism.

One object of the present invention is to provide a machine for imparting bulk to a strand of twisted continuous yarn, stretching the bulked strand and winding it into a package in one continuous operation.

Another object of the present invention is to provide a machine for imparting bulk to a twisted strand of continuous filament yarn wherein breakage of the strand being operated upon will cause all of the elements of the machine to stop their operation.

Another object of the present invention is to provide a machine for imparting bulk to a twisted strand of continuous filament yarn wherein all of the elements thereof can be started simultaneously.

Another object of the present invention is to provide an apparatus for imparting bulk to a twisted strand of continuous filament yarn wherein all the elements thereof can be stopped substantially simultaneously.

Other objects of the present invention will in part be obvious and will in part appear hereinafter.

The invention accordingly comprises the apparatus possessing the construction, combination of elements and arrangement of parts which are exemplified in the following detailed disclosure, and the scope of the application of which will be indicated in the claims.

For a fuller understanding of the nature and objects of the invention, reference should be had to the following detailed description taken in connection with the accompanying drawing wherein:

Fig. 1 is a front elevation of a section of the machine of the present invention;

Fig. 2 is a side elevation corresponding to Fig. 1; and

Fig. 3 is a detail view of a rotating yarn guide.

2

The machine of the present invention is preferably a multiple unit machine. That is to say, it is provided with a plurality of identical yarn processing units along its length on both sides thereof. Inasmuch as all units are identical, only one will be described herein; and

Each unit of the present invention includes three yarn handling stations or positions. Each position includes a positively driven roller which in the first two stations drives a form of idler roll to forward the strand of yarn being operated on, and the third operates a winding spindle to stretch the bulked yarn and wind it in a package. An aspirator for forming loops in the filaments of the strand being operated on is positioned between the first and second rollers and receives the strand of yarn forwarded by the first roller and has the bulked yarn drawn therefrom by the second roller. The winding spindle driven by the third roll and the idler rolls driven by the first two rollers are interconnected in such a fashion that when a stop motion mechanism incorporated with

20 the winding spindle is actuated to disengage the winding spindle from its driving roller, the two idler rolls cooperating with the first two rollers are also disengaged to prevent any further feeding of the yarn. The winding spindle and the two idler rollers are further interconnected for simultaneous movement by a manually operated member whereby all three of them can be placed in contact with their respective driving roll at substantially the same instant to start the bulking operation.

A plurality of spaced apart vertical frame members 10 are secured to base members 12 and are held together to form a unitary structure by means of longitudinal members 14, 16, 18, 20 and 114. Cross members 24 secured to vertical frame members 10 support a rail or shelf 26 longitudinally of both sides of the machine adjacent base members 12. Shelf 26 is adapted to carry a plurality of yarn packages P that serve as the supply for strands of yarn Y. Three identical brackets 28, 30 and 32 are carried by vertical frame members 10 and are spaced substantially equal distances from each other. Shafts 34, 36 and 38 are rotatably carried by brackets 28, 30 and 32 respectively, and are positively driven by any convenient source of power, not shown. Preferably shaft 34 rotates at a speed in the order of 35% faster than shaft 36 and in the order of 20% faster than shaft 38. 45 Rollers 40, 42 and 44 are carried for rotation by shafts 34, 36 and 38 respectively.

A bobbin hanger 46 is secured to longitudinal member 14 to permit winding arbor 48, or the package being wound thereon, to contact roll 44 and to be driven thereby to wind said package. Preferably bobbin hanger 46 includes a journal member 50 secured to longitudinal member 14 and having a shaft 52 rotatably journaled therein. An arm 54 is fixedly secured to one end of shaft 52 for pivotal movement therewith. Winding arbor 48 is rotatably mounted on the forward end of arm 54. A stop-motion mechanism, which may be of any convenient type, as for example such as is disclosed in United States Patent No. 2,649,253, but which preferably is similar to the stop-motion mechanism disclosed 60 in the application for United States Letters Patent Serial No. 320,065, filed November 12, 1952, by D. G. Soussloff and R. V. Tata, is incorporated in journal member 50. Preferably the stop-motion mechanism includes a depending hook 56 pivotally carried by a rearward extension of arm 54 and movable into and out of engagement with an oscillating finger 58 to pivot arbor 48 upwardly out of engagement with its driving roll 44 when said hook and finger are engaged. Oscillating fingers 58 are carried by rock shaft 59 which is preferably driven by the same source of power employed to rotate shafts 34, 36 and 38. A yarn engaging counterbalanced breakage lever 60 is connected to hook 56 and

is adapted to be engaged by the running strand of yarn, in a manner well known in the art, whereby said lever is held against movement but is urged by its counter-balance 61 to swing upwardly when the running strand of yarn breaks or is exhausted. Upward movement of breakage lever 60 swings depending hook 56 into engagement with oscillating finger 58 to cause arm 54 to be lifted upwardly. Longitudinal members 16 and 18 carry journal members 62 and 64 similar to journal member 50 but with the stop-motion mechanism omitted. Arms 66 and 68, similar to arm 54 are secured to shafts 70 and 72 journaled in said journal members 62 and 64. Rolls 74 and 76, generally similar to arbor 48 but provided with a rubber yarn engaging surface are rotatably secured to the free ends of arms 66 and 68 respectively for movement into engagement with rolls 42 and 40.

The opposite ends of shafts 52, 70 and 72 have levers 78 fixedly secured thereto so that downward movement thereof will lift said arms and upward movement thereof will permit said arms to descend. The free ends of levers 78 are bifurcated and slidably receive a tension rod 80. The uppermost end of rod 80 is connected to one end of spring 82, the other end of which is secured to a longitudinal member 84, and the lowermost end of tension rod 80 is secured to one end of a flexible member 86 as, for example a metallic cable or tape. Flexible member 86 passes around pulleys 88 and 90 and has its other end secured in any convenient manner to a foot operated lever 92 which is pivotally carried by longitudinal member 22. Abutments or stops 98 are fixedly secured to tension rod 80 adjacent the upper surfaces of levers 78. It will be seen, therefore, that depressing lever 92 will pull rod 80 downwardly and will cause abutments 98 to engage levers 78 to simultaneously lift rolls 74 and 76 and arbor 48 from their respective driving rollers. Conversely, releasing holding pressure on lever 92 will permit rod 80 to be drawn upwardly by its spring 82 thus lowering rolls 74 and 76 and arbor 48 into contact with their driving rolls to simultaneously start the operation of the machine, and at the same time lifting lever 92. Nuts 94 and 95 are adjustably carried by rod 96 to limit the movement of lever 92.

Arms 54, 66 and 68 are also interconnected by means of rod 100 which passes through aligned openings formed in ears projecting from the respective arms. An abutment 102 is fixed to the upper end of rod 100 to be engaged by the upper surface of the ear carried by arm 54. Abutments 104 and 106 are fixed to rod 100 adjacent the lower surfaces of the ears affixed to arms 66 and 68 respectively. Rod 100 and abutments 102, 104 and 106 function to disengage rolls 74 and 76 from their driving rolls 42 and 40 in the event of yarn breakage or exhaustion. When the strand of yarn being treated breaks or is exhausted, breakage lever 60 is permitted to rise causing the stop-motion mechanism to lift arm 54 to disengage the winding package from roller 44. Upward movement of arm 54 causes its ear to lift rod 100, and the upward movement of said rod causes abutments 104 and 106 to lift rolls 74 and 76. Latch means are preferably provided to hold arms 54, 66 and 68 in their elevated positions after they have been lifted by the operation of the knock-off mechanism. Any convenient means can be provided for releasing the latches, as for example, the finger pieces 108.

A tension device 110 having a pair of yarn guides 111 and 112 incorporated therewith is supported above package P by longitudinal bar 114 carried by upstanding arm 116 secured to bracket 28. A horizontal pipe 118, suitably connected to a source of compressed air, is secured to upstanding arm 120 carried by bracket 30. Aspirator 122 is connected to pipe 118 by means of tube 124 and valve 126. Yarn guiding rod 128 is positioned beneath the inlet to aspirator 122 and is supported by arm 130 in turn carried by arm 120.

A reciprocating yarn guide 132 is provided for travers-

5 10 15

ing the bulked strand of yarn longitudinally of winding arbor 48. Guide 132 is supported and reciprocated by traverse rod 134 which is journaled for longitudinal sliding movement in upstanding arm 136 carried by bracket 32. Traverse rod 134 may be reciprocated by any convenient means as, for example, a cam located adjacent one end of the machine and driven by the source of power which rotates rolls 40, 42 and 44. A rotatable horizontal yarn guiding bar 138 is also supported by upstanding arm 136 slightly above and outside of traverse rod 134. Bar 138 is preferably rotated by suitable gearing, not shown, connected to shaft 38. A rotating yarn guide 140, Fig. 3, of the type disclosed in U. S. Patent No. 2,631,787, issued March 17, 1953, to R. V. Tata, is secured to rotatable bar 138 at a position slightly outside of the traverse stroke of guide 132, but within the length of a yarn receiving core carried by arbor 48. Rotating guide 140 is a generally disc-like member provided with radially extending fingers 142 that hold a running strand of yarn at one side thereof, the right hand side as viewed in Fig. 1, for a predetermined length of time and then pass the strand to the other side, to be picked up by guide 132, by engaging said strand in the space between any two of the fingers 142.

20 25 30 35 40 45 50 55 60 65 70 75 80 85 90 95

The above described apparatus functions in the following manner. A package of yarn P is positioned on shelf 26 in alignment with rollers 40, 42 and 44. Rolls 74 and 76 and winding arbor 48 are lifted until their latching mechanism engages to hold them in their raised positions. Strand of yarn Y is drawn upwardly from package P and is threaded through guide 112, tension 110 and guide 111. From guide 111 strand Y passes generally horizontally in a rearward direction and is passed around roll 76. From roll 76 the strand is led upwardly and forwardly to pass beneath guide rod 128 and thence upwardly through aspirator 122. Valve 126 is preferably opened at this time so that air passing through said aspirator will assist in threading said strand therethrough. Upon leaving the upper end of aspirator 122 the strand is drawn rearwardly at approximately 90° to axis of said aspirator and passes around roll 74. From roll 74 the strand is led upwardly and forwardly to pass around rotatable bar 138. The yarn is positioned on bar 138 on the right hand side, as viewed in Fig. 1, of rotating yarn guide 140. After leaving rotating bar 138 the strand is led rearwardly and is secured to arbor 48. At this time, lever 92 is depressed to draw tension rod 80 downwardly, and the latches holding arms 54, 66 and 68 in their raised position are released by means of latch finger pieces 108 to permit said arms to swing downwardly until their levers 78 engage abutments 98. Lever 92 is then raised to lower arms 54, 66 and 68 to simultaneously engage rolls 74 and 76 with rollers 42 and 40 and winding arbor 48 with roller 44. As soon as rolls 74 and 76 and winding arbor 48 contact their respective driving rollers, yarn is drawn from package P by roller 76 and fed to aspirator 122 which sucks the strand in its lowermost end and discharges it from its uppermost end. The strand of yarn Y as it emerges from aspirator 122 is immediately drawn out of the stream of air by roll 74 and the now bulked strand is passed onwardly by that roll to winding arbor 48. Shaft 138 rotates at a relatively slow speed so that the initial run of yarn is wound adjacent one end of the package core carried by arbor 48 in the form of a tail. The speed of shaft 138 is such that the running strand of yarn is not transferred to traverse guide 132 until the process practiced by the apparatus is in balance and said running strand arriving at arbor 48 is completely treated. In other words, rotating guide 140 causes the initial length of waste or improperly treated yarn to be wound adjacent the end of the package so that it can be readily removed and thus not be incorporated in any subsequent manufacturing operation.

Driving roll 40 rotates faster than either roll 42 and

44 and roll 44 rotates faster than roll 42. The difference in speed between roll 40 and roll 42 determines the amount of bulking that is imparted to the strand being treated. The slower roll 42 runs relative to roll 40, the larger will be the loops formed by aspirator 122 and the greater their frequency. Roll 44 causes winding arbor 48 to wind the yarn at a speed faster than it is advanced by roll 74. Therefore, the winding operation stretches the textured yarn a certain amount to standardize its diameter and to remove any irregularities that might occur in the yarn as it passes through aspirator 122. The final diameter or denier of the yarn being treated is determined and controlled by the speed of roller 44 relative to the speed of roll 40.

In the event strand of yarn Y breaks anywhere between package P and winding arbor 48, breakage lever 60 will be permitted to rise to initiate the action of the stop-motion mechanism associated with arm 54. The stop-motion will then lift said arm 54, and arm 54 acting through rod 100 and abutments 102, 104 and 106 will lift arms 66 and 68. Therefore, should the strand of yarn break between rollers 40 and 42 or between rollers 42 and 44 the feeding of the yarn will be effectively stopped.

Since certain changes may be made in the above apparatus without departing from the scope of the invention herein involved, it is intended that all matter contained in the above description or shown in the accompanying drawing shall be interpreted as illustrative and not in a limiting sense.

What is claimed is:

1. In an apparatus for imparting bulk to a strand of yarn wherein means are provided for inserting loops into the individual filaments making up a running strand of yarn, the combination comprising a driving roller for rotating a winding package to wind the bulked strand of yarn, means supporting said package for movement towards and away from said roller, a pair of spaced driving rollers, a pair of yarn engaging rolls, means supporting said rolls for movement towards and away from said last mentioned driving rollers, one of said yarn engaging rolls being positioned to feed said strand to said loop inserting means at a speed greater than the speed at which it is wound on said package and the other being positioned to draw it therefrom and feed it to said winding package at a speed less than the speed at which it is wound on said package, stop-motion means associated with said package supporting means to move the winding package out of contact with its driving roller upon breakage of said strand, and means interconnecting said package supporting means and said roll supporting means whereby movement of said package supporting means by said stop motion moves said yarn engaging rolls out of contact with their driving rollers.

2. In an apparatus for imparting bulk to a strand of yarn wherein means are provided for inserting loops into the individual filaments making up a running strand of

yarn, the combination comprising a driving roller for rotating a winding package to wind the bulked strand of yarn, means supporting said package for movement towards and away from said roller, a pair of spaced driving rollers, a pair of yarn engaging rolls, means supporting said rolls for movement towards and away from said last mentioned driving rollers, one of said yarn engaging rolls being positioned to feed said strand to said loop inserting means at a speed greater than the speed at which it is wound on said package and the other being positioned to draw it therefrom and feed it to said winding package at a speed less than the speed at which it is wound on said package, and manually operable means interconnecting said package supporting means and said roll supporting means to permit said supporting means to be moved together to engage the winding package and said rolls with their respective driving rollers substantially simultaneously.

3. In an apparatus for imparting bulk to a strand of yarn wherein means are provided for inserting loops into the individual filaments making up a running strand of yarn, the combination comprising a driving roller for rotating a winding package to wind the bulked strand of yarn, means supporting said package for movement towards and away from said roller, a pair of spaced driving rollers, a pair of yarn engaging rolls, means supporting said rolls for movement towards and away from said last mentioned driving rollers, one of said yarn engaging rolls being positioned to feed said strand to said loop inserting means at a speed greater than the speed at which it is wound on said package and the other being positioned to draw it therefrom and feed it to said winding package at a speed less than the speed at which it is wound on said package, stop-motion means associated with said package supporting means to move the winding package out of contact with its driving roller upon breakage of said strand, means interconnecting said package supporting means and said roll supporting means whereby movement of said package supporting means by said stop-motion means moves said yarn engaging rolls out of contact with their driving rollers, and manually operable means interconnecting said package supporting means and said roll supporting means to permit said supporting means to be moved together to engage the winding package and said rolls with their respective rollers substantially simultaneously.
